PLIER SAFE

Filed May 21, 1927

INVENTOR.

F. F. Hildebrand
BY Watson E. Coleman
ATTORNEY.

UNITED STATES PATENT OFFICE.

FREDRICK F. HILDEBRAND, OF SYKESTON, NORTH DAKOTA.

PLIER SAFE.

Application filed May 21, 1927. Serial No. 193,297.

This invention relates to devices for holding pliers and like tools in the pocket of a pair of overalls.

Practically all makes of overalls are provided with a pocket for pliers, but there is no means for retaining the pliers in the pocket so that when the workman bends over the pliers will not fall out, which means will permit the ready removal of the pliers.

The general object of my invention is to provide a safe, as it may be termed, adapted to be disposed in and attached to the wall of an overall pocket, which is so formed as to retain the pliers therein but which will permit the easy removal of the pliers.

A further object is to form the safe as a metallic frame or case so constructed as to receive the pliers and having a lid or cover at the mouth end disposed normally above the opening of the pocket, which cover may be readily released and opened to permit the removal or insertion of the pliers.

Other objects have to do with the details of construction and arrangement of parts as will appear more fully hereinafter.

My invention is illustrated in the accompanying drawing, wherein:—

Figure 1 is a fragmentary face view of a portion of a pair of overalls with my plier safe applied thereto;

Figure 2 is a vertical sectional view through the plier safe;

Figure 3 is a section on the line 3—3 of Figure 2;

Figure 4 is a section on the line 4—4 of Figure 2.

Referring to this drawing, it will be seen that the plier safe consists of the longitudinal members 10. These are preferably made of metallic strips about $\frac{1}{2}$ " wide and about $\frac{1}{16}$ " or $\frac{1}{8}$ " thick. To the upper end of one of these strips there is hinged the lid or cover 11 provided with a sliding latch 12, the opposite strip 10 being formed with a perforation or keeper 13 to receive the extremity of the latch.

I have heretofore referred to the strips 10 as if they were separate pieces but, as a matter of fact, the strips 10 are formed from a single piece of metal bent into a U shape so as to provide a lower end 14 for the safe. The lower ends of the strips 10 are connected by means of the side plates 15 which are cast, riveted or otherwise attached to the

portions 10 so as to form a socket for the lower end of the pliers A. Midway between the portion 15 and the lid 11, and preferably nearer the lid than the portion 15, there is disposed the side plates 16. These may be cast with the portions 10 or riveted or otherwise attached thereto. Each of these side plates 16 at its middle is outwardly bulged, as at 17, and one of these side plates is provided with perforations 18 whereby to fasten the safe within the pocket of the garment, either by riveting, stitching or any other suitable means.

The safe as heretofore described is disposed within the pocket B of the overall so that the upper end of the safe projects slightly above the upper end of the pocket for convenient access. By having the side plates 16 outwardly bulged at 17, the bolt a of the pliers A is accommodated so that the projecting ends of the bolt will not catch on the side plates as the pliers are withdrawn or inserted. The safe described will prevent pliers from sliding out of the pocket and becoming lost.

I claim:—

1. A plier safe of the character described including longitudinally extending members joined at their lower ends and supporting a lid at their upper ends, side pieces attached to the lower ends of the longitudinal members and together with the longitudinal members constituting a socket for the jaw ends of the pliers, and side members attached to said longitudinal members in a position spaced from the lid, said side members being outwardly bulged at their middles to permit passage of the plier rivet.

2. A plier safe of the character described comprising a strip of thin metal having an approximate U-shape, side members attached to the right end of the U-shaped strip of metal to thereby form a socket for the reception of the jaw end of a pair of pliers, a lid hinged to one arm of the U-shaped strip and having a latch engaging the other arm thereof, and side members attached to the arms of the U-shaped strip below said lid, each side member being outwardly bulged at its middle to permit the passage of the plier rivet.

In testimony whereof I hereunto affix my signature.

FREDRICK F. HILDEBRAND.
